(57) **CLAIM**

The ornamental design for a cable guide, as shown and described.

DESCRIPTION

FIG. 1 is a top isometric view of a first embodiment of a cable guide;

FIG. 2 is a bottom isometric view of the cable guide shown in FIG. 1;

FIG. 3 is a front elevational view of the cable guide shown in FIG. 1;

FIG. 4 is a right side elevational view of the cable guide shown in FIG. 1;

FIG. 5 is a rear elevational view of the cable guide shown in FIG. 1;

FIG. 6 is a left side elevational view of the cable guide shown in FIG. 1;

FIG. 7 is a top plan view of the cable guide shown in FIG. 1;

FIG. 8 is a bottom plan view of the cable guide shown in FIG. 1;

FIG. 9 is another top isometric view of the cable guide shown in FIG. 1, wherein the threaded fastener and nut depicted as broken lines have been omitted for clarity of disclosure;

FIG. 10 is a top isometric view of a second embodiment of the cable guide;

FIG. 11 is a bottom isometric view of the cable guide shown in FIG. 10;

FIG. 12 is a front elevational view of the cable guide shown in FIG. 10;

FIG. 13 is a right side elevational view of the cable guide shown in FIG. 10;

FIG. 14 is a rear elevational view of the cable guide shown in FIG. 10;

FIG. 15 is a left side elevational view of the cable guide shown in FIG. 10;

FIG. 16 is a top plan view of the cable guide shown in FIG. 10;

FIG. 17 is a bottom plan view of the cable guide shown in FIG. 10; and,

FIG. 18 is another top isometric view of the cable guide shown in FIG. 10, wherein the threaded fastener and nut depicted as broken lines have been omitted for clarity of disclosure.

The threaded fastener and nut represented as broken lines depict environment that forms no part of the claimed design.
